SEPARABLE VALVE

Styles T. Howard, Jeffersonville, Ind.

Application August 9, 1941, Serial No. 406,202

5 Claims. (Cl. 137—69)

(Granted under the act of March 3, 1883, as amended April 30, 1928; 370 O. G. 757)

The invention described herein, if patented may be manufactured and used by or for the Government for governmental purposes without the payment of any royalty thereon.

This invention relates to an improved separable valve and more particularly to a form especially adapted for use in connection with a fuel line and control valve coupling structure covered by separate application and provides a valve that may be quickly separated for cleaning or replacement of parts and was designed for use more particularly in the recently constructed Army portable range.

The object in view is to provide a simple, durable and inexpensive valve that may be produced with the minimum machine work.

A further object in view is to provide a valve having few parts of sturdy construction.

Another object is to provide for the rapid disassembling, cleaning or replacement of the parts and assembling of same repeatedly without danger of injury to the parts of the valve and the inaccurate functioning of the parts that would otherwise result.

The above and other objects will appear in the following description and be specifically pointed out in the appended claims.

While the preferred embodiment of this invention is shown and described, it will be understood that slight changes in form and minor details of construction may be resorted to without departing from the spirit of the invention or fall beyond the scope of the claims.

Similar numerals indicate corresponding parts in all the figures of the drawing in which:

Fig. 1 is a fragmentary view of a portion of a burner with the improved valve in position.

Fig. 2 is an enlarged vertical longitudinal section of the valve.

Fig. 3 is a plan view of the valve.

Fig. 4 is a side elevation of a portion of the valve.

Fig. 5 is a section on line 5—5 of Fig. 2.

Reference now being had to the drawing by numerals, 1 indicates the valve mounted in a sleeve 2 of a supporting plate 3, said valve as shown discharging into the mixing chamber 4 of a burner indicated at 5, said burner being provided with a fuel tube 6 and an extension 7 adapted to be in communication with the valve through a lateral opening therein. The supporting plate is provided with a slot 8 to be described later.

The valve consists of the body 9, the stem 10, the gland 11, the jet 12 and the nut 13.

The body 9 of the valve is provided with a lateral fuel inlet opening 14, to which a liquid or vapor fuel tube 7 may be connected in any preferred manner, the form shown being a contact joint formed by ground male and female surfaces on and in the end of the fuel tube and said opening in the valve body respectively. Said manner of joining the fuel tube and the valve being shown as the one most desirable with the present Army portable range, to enable quick disassembling and assembling of the parts as is required by the Army, due to practically continuous use of the burner, of which the form of valve here shown is a part.

The valve body 9 of the valve is provided with a projecting pin 15 that, when the valve is mounted on a supporting plate 3, is adapted to pass through the slot 8 in the plate and when the valve body is given a slight rotary movement the pin 15 will be caused to pass in rear of the plate at one side of slot 8 and lock the valve in place.

The body 9 of the valve is provided with a bore having a relatively reduced portion 16, the screw threaded portion 17, a cylindrical portion 18, an inner packing shoulder 19 and an enlarged partly threaded portion 20. The discharge end of the body portion is concave as shown at 21.

The jet 12 is provided with a convex surface 22 adapted to be seated in the concave end 21 of the body 9 and forms a continuation of said body. The jet is further provided with a needle valve seat 23 and a shoulder 24.

The nut 13 is threaded at 25 on the end of the body 9 of the valve and is provided with an internal shoulder 26 adapted to contact with shoulder 24 of the jet and secure same in place, and also provide for the quick removal of said jet for cleaning or replacement purposes.

The valve stem 10 consists of a combined needle valve point 27, having a plurality of fuel passages 28, which occupies the reduced portion 16 of the bore in the body of the valve with which the lateral fuel inlet opening 14 communicates. By reference to Fig. 5 it will be seen that the needle portion of the stem 10 may be of triangular form as shown, having said fuel passages 28 adapted to provide a direct passage for fuel from opening 14 out through the needle valve in any adjustment of the stem, either in a rotated or a longitudinal movement.

The valve stem is provided with a threaded portion 29 adapted to operate in the threaded portion 17 of the body 9. The valve stem is further provided with a smooth cylindrical portion 30 adapted to extend into and operate at its end

in the smooth bore portion 18 of the body and extend through the packing 31 and packing land 11 which is threaded at 32 in the body 9. Said stem extending out through the end of the gland and having mounted thereon the knob 33 secured by split pin 34 to enable the removal of the knob, the stem from the body and the gland from the stem. 5

To facilitate the disassembling of parts of the valve, flattened portions 35 are provided on opposite sides of the body portion 9 to which may be applied a monkey wrench or the like when removing gland 11 and nut 13 from the body portion. 10

Having fully described my invention, what I claim and desire to secure by Letters Patent is: 15

1. The combination with a supporting plate having a sleeve provided with a lateral inlet opening a bayonet slot and a supply tube of a fluid control valve comprising a body provided with a bore having a reduced portion, a screw threaded portion, a smooth portion, and an enlarged partly screw threaded portion adapted to receive a packing and a packing gland, said lateral fuel inlet opening in communication with said reduced portion of the bore and said supply tube adapted to admit fuel to said portion, a locking pin extending from the valve body adapted to cooperate with said bayonet slot to secure said valve in the sleeve, and a concave end, a removable jet adapted to form a continuation of the body having a convex end, adapted to seat in the concave end of the body, a needle valve seat and a shoulder, a nut threaded on the end of the body having a shoulder adapted to contact the shoulder of the jet and clamp same in place, a valve stem having an elongated needle extending from said needle valve seat to beyond said lateral fuel inlet opening and having a plurality of fuel passages adapted to permit the passage of fuel from said fuel inlet to the valve in any portion of the valve stem, a threaded portion operating in the threaded portion of the body adapted to longitudinally adjust the valve stem, a cylindrical portion adapted to operate in the cylindrical portion of the body and form a support for the valve stem, through the packing and packing gland, said stem provided at its outer end with a removable knob for the operation of the stem and permit the disassembling of parts of the valve. 40

2. The combination with a supporting plate having a sleeve provided with a lateral opening, and a bayonet slot, and a supply tube extending through the sleeve, of a fluid control valve having a body, a lateral fluid inlet opening in communication with and forming a seat for the lower end 45

of said tube, a removable jet having a needle valve seat adapted to form a continuation of the body, removable means for securing the jet in place and a needle valve adapted to control the flow of fuel through the jet. 5

3. The combination with a supporting plate having a sleeve provided with a lateral opening, and a supply tube adapted to extend through said sleeve, of a fluid control valve having a body provided with a central bore and a lateral fuel opening in communication with and forming a seat for the lower end of said tube, means for supplying fuel to said opening, a removable jet having an internal shoulder; a needle valve seat adapted to form a continuation of the body and said bore of the body, a valve stem having a needle valve adapted to operate in the valve seat of the jet to control the flow of fuel and a removable nut threaded on the body having an internal flange adapted to contact said external flange of the jet and secure said jet in place. 10

4. The combination with a supporting plate having a sleeve provided with a lateral fuel supply pipe opening, and a bayonet slot, of a fluid control valve having a body provided with a projecting pin adapted to engage said bayonet slot a central bore having a reduced portion and a lateral fuel opening in communication with said reduced portion of the bore, a removable fuel supply tube extending through said flange and seated at its lower end in said opening in the valve body adapted with said pin and bayonet slot to removably lock the valve in place a removable jet having a needle valve seat adapted to form a continuation of the reduced portion of the bore of the body, a valve stem having an elongated needle portion provided with a needle valve at its end adapted to operate in said needle valve seat of the jet and cutaway portions adapted to provide fuel passages from said fuel inlet opening to said needle valve. 20

5. The combination with a supporting plate having a sleeve provided with a lateral opening and a removable supply tube extending through said opening, of a fluid control valve having a body, a lateral fuel inlet opening in communication with and providing a seat for the lower end of said supply tube, a removable jet arranged at the end of the valve body having a needle valve seat, removable means for securing the jet in place, and a needle valve having an elongated reduced portion to provide for the passage of fuel from said supply tube, and said needle valve seat adapted to control the flow of fuel through the jet. 30
